UNITED STATES PATENT OFFICE.

JOSEPH W. TEAGUE, OF SALT LAKE CITY, UTAH.

OIL-CAN.

1,108,022.

Specification of Letters Patent. Patented Aug. 18, 1914.

Application filed April 12, 1913. Serial No. 760,785.

To all whom it may concern:

Be it known that I, JOSEPH W. TEAGUE, a citizen of the United States, residing at Salt Lake City, in the county of Salt Lake 5 and State of Utah, have invented certain new and useful Improvements in Oil-Cans; and I do hereby declare the following to be a full, clear, and exact description of the invention, such as will enable others skilled in 10 the art to which it appertains to make and use the same.

This invention relates to new and useful improvements in oil cans, and has for its object to provide a device of the above character which is adapted to be used for oiling 15 large surfaces, tools, etc., as well as the ordinary uses to which an oil can may be put.

In the construction of my improved device I provide an absorbing member upon which 20 the oil is adapted to be dropped, and the member then rubbed over the surface that is to be oiled.

A further object of my invention is to provide a device which will have such a surface oiling member so arranged that the 25 same may be carried within a pocket formed in the oil can, so that at all times the device will be ready for use.

With the above and other objects in view 30 I will now proceed to describe my invention in the following specification and accompanying drawings, in which,

Figure 1 is a transverse sectional view of my improved oil can, showing the surface 35 oiling member in place in the base of the can; and Fig. 2 is a view of the surface oiling member as it would appear when removed, and showing the oil can in position for placing oil on to the absorbing mate- 40 rial.

Referring to the drawings by characters of reference, 5 indicates the body portion of an oil can of the usual construction. This body portion is preferably composed of the 45 cylindrical side wall 6, the dome shaped top 7 carrying a screw threaded collar 8, which is adapted to be engaged by the screw threaded sleeve 9 of the spout 10.

The bottom 11 of the oil can is preferably 50 spaced substantially one-half the distance up the length of the sides, and thereby provides a depending flange 12 which, in combination with the bottom of the oil can 11,

forms a receptacle which is adapted to receive the surface oiling member 13. This 55 surface oiling member 13 preferably comprises the cylindrical side walls 14 and the bottom 15, which is extended, as clearly shown at 16, and its outer edges bent up to form the upstanding flange 17, which is 60 adapted to form a seat for the lower terminal of the wall 12, and also to act as a receptacle for overflowing oil which may run off the top of the surface oiling member. A suitable absorbing material 18 is prefer- 65 ably provided and is adapted to be held firmly in the receptacle 13 formed by the wall 14 and the bottom 15.

Adjacent the upper extremity of the wall 14 I preferably provide a circumferential 70 rib 19 which extends outwardly from said wall and is adapted to seat in a recess 20 formed in the wall 12 of the oil can. It will be seen that in this manner I provide a means whereby the surface oiling member is 75 held rigidly in the bottom of the oil can and cannot be removed except as the user so desires.

In use, when it is desired to oil the surface of a table, tools, and the like, the surface oiling member is removed from its position within the receptacle formed in the base of the oil can, and the same placed so that the absorbing material will be upward. The oil can is then inverted and the liquid 80 contained therein will flow downwardly through the spout and on to the absorbing material, and it will be seen that in this manner such devices as mentioned above may be easily and quickly oiled without the 85 necessity of carrying extra cloths and the like. It will also be noted that the oil can used may be made of any preferred type and of a size to suit the user, and that my invention resides in the provision of a receptacle 90 within the base of an oil can which is adapted to receive the surface oiling member, and thereby keep the whole in a compact space. 95

Having thus fully described my invention what I claim is:

In combination with an oil can comprising a cylindrical body portion, a cover and a spout, a bottom spaced from the lower extremity of the cylindrical body portion, a rib formed adjacent the bottom and intermediate the lower extremity of the cylindri- 100 105

cal body portion, a surface oiling member comprising a cylindrical body portion and a bottom, an extension formed on the edge of the bottom, a flange secured to the extension, 5 said flange being spaced from the side wall to form a receptacle to receive overflowing oil, an absorbent material secured within the surface oiling member, said absorbent mate-

rial being adapted to retain oil when the device is in operation.

10 In testimony whereof I affix my signature in presence of two witnesses.

JOSEPH W. TEAGUE.
